FRAME

F. Haskell Fredman, Rochester, N. Y.

Application May 9, 1938, Serial No. 206,711

4 Claims. (Cl. 20—92)

This invention relates to frames for windows, doors, storm sash, screens, etc., and has for its object to provide an improved simplified construction for making sash frames.

- 5 A further object of this invention is to construct a frame with novel metal corners which, besides holding the rails of the frames together, increases the rigidity of the frames by reinforcing the corners thereof.
- 10 Another object of this invention is to provide the frame with novel forms of rails in combination with metal corners which permit the rails to be accurately fitted on all sides of the frame including the corners thereof.
- 15 These and other objects and attendant advantages of the invention will become more readily apparent from the detailed description thereof which follows, reference being had to the accompanying drawing in which:
- 20 Figure 1 is a perspective front view of the corner construction of a frame in accordance with my invention.

Figure 2 is a perspective rear view of the corner construction of a frame made in accordance with my invention.

Figure 3 is a vertical sectional view of the frame, the section being taken on the line 3x—3x of Figure 1.

Figure 4 is a similar sectional view of the frame 30 when used for a storm sash.

Figure 5 is a detail perspective view of one of the metal corners which fasten the rails of a frame together.

In the several figures of the drawing like reference numerals indicate like parts.

The construction of the frame forming the subject matter of this invention includes the use of rails of uniform cross section for the sides, top and bottom of the frame. These rails, indicated by reference numeral 1 and illustrated in cross section in Figures 3 and 4, have a portion of their outer edge cut away to provide a rabbet 2 thereon with a narrow groove 3 extending into the rail at the inner edge of the rabbet parallel 40 thereto. In this way each rail is provided with a fitting ridge or ledge 4 on the outside thereof.

The inner edge of each rail is rabbeted at 5 to have the molding 6 nest therein and clamp the edge of a screen 7 to the rail. On the inside of 50 the rail parallel to the rabbet 5 and suitably spaced from it is the narrow groove 8. This groove is thus located on the inside of the rail substantially opposite to the groove 3 provided in the outside of the rail. In the construction 55 of a frame the ends of the rails are brought to-

gether in a miter joint and the mitered ends are held together by a corner bracket 9. These brackets are formed of sheet metal and provide a rectangular channel with flanges 10, 10 overhanging the channel as illustrated in Figure 5. 5

In connecting a pair of rails the mitered ends thereof are telescoped from opposite ends into the rectangular channel of the corner bracket 9 with the flanges 10, 10 thereof projecting into the grooves 3 and 8 in the rails. After the rails 10 are brought together in the corner bracket in this way nails or screws are driven thru the metal back or sides thereof into the rails to lock the ends of the rails in place in the bracket and cause them to be rigidly connected and held in place 15 in the bracket at right angles to each other.

With the rails fastened together in this manner, the fitting ridge 4 of each rail extends beyond the outside of the metal corner brackets which hold the rails together so that this fitting ridge continuously extends around the completed frame to provide for an accurate fitting of the frame into a window or door frame by means of this ridge. The frame is usually made slightly larger than the opening into which it is 20 to be fitted and the fitting ridge makes it possible to accurately finish the edge of the frame to its proper dimension after it has otherwise been completed. The use of the novel metal corners and the manner in which they hold the rails 25 together make this possible. In Figure 3 reference numeral 11 indicates the cross section of a window or door frame into which a frame, made up in accordance with my invention, is fitted as above pointed out. 30

When a glass panel 12 is to be mounted in the frame as illustrated in cross section in Figure 4, the rabbet 5 is provided with a shoulder 13 so as to have the mold 14 provide a channel between it and the rail 1 in which the glass panel 40 is held in place when the molding is fastened to the rail by suitable wire nails 15. 35

The shoulder 13 is preferably provided by a spacing strip 16 which is placed or fastened into the rabbet 5. The spacing strip used is slightly 45 thicker than the thickness of the glass panel which is to be mounted in the frame so that when the molding 14 is fastened in place it cannot exert pressure on the edge of the panel and thereby cause it to break.

I claim:

1. A frame made up of a plurality of rails of uniform cross section having a rabbet on the outer edge of each rail on one side thereof, a locking groove extending inwardly of the inner cor- 55

ner of the rabbet, a second locking groove on the inner edge of each rail intermediate the sides thereof and substantially opposite to said first locking groove, locking brackets connecting said 5 rails by engaging one side and the outer and inner edges of adjacent rails, each locking bracket comprising an angular channel, flanges on the sides of said channel arranged to partially overhang said channel, said flanges engaging into 10 said locking grooves to guide and hold the sides of said channel against the outer and inner edges of said rails in said locking bracket.

2. A frame made up of a plurality of rails, a 15 locking groove in one edge intermediate the sides of said rails, a rabbet in the other edge on one side of said rails, a second locking groove extending inwardly of the inner edge of said rabbet toward said first locking groove, a locking bracket 20 embracing one side of said rails, the bottom of the rabbet and a portion of the inner edge of said rails, and means provided on said locking bracket to engage said locking grooves to hold

said rails in said locking bracket in a predetermined position with relation to each other.

3. A wood frame made up of a plurality of rails having a uniform cross section, metal brackets embracing one side and part of the outer and inner edges of the ends of successive rails on the outside and inside of the frame with a portion of the outer edge of each rail projecting past the parts embraced by the metal brackets to provide a fitting edge around the frame and locking 10 means cooperating with said brackets to lock said brackets to said rails.

4. A wood frame made up of a plurality of rails having a uniform cross section with a projecting fitting edge, metal brackets embracing one side 15 and part of the outer and inner edges of the ends of successive rails on the outside and inside of the frame and within the projecting fitting edge of the outside of the frame so as to keep the fitting edge of the frame exposed over its entire perimeter and locking means carried by said metal brackets to lock said brackets to said rails. 20

F. HASKELL FREDMAN.
